US00D978444S

(12) **United States Design Patent** (10) **Patent No.:** **US D978,444 S**
Chen (45) **Date of Patent:** **** Feb. 14, 2023**

(54) **ELECTRONIC EARMUFF**

(71) Applicant: **Zubang Chen**, Ningbo (CN)
(72) Inventor: **Zubang Chen**, Ningbo (CN)
(**) Term: **15 Years**
(21) Appl. No.: **29/795,182**
(22) Filed: **Jun. 17, 2021**
(51) LOC (14) Cl. **29-02**
(52) U.S. Cl. **USPC D29/112**

(58) **Field of Classification Search**

(57) **CLAIM**

The ornamental design for an electronic earmuff, as shown and described.

DESCRIPTION

FIG. 1 is a perspective view of an electronic earmuff showing my new design;
FIG. 2 is a front view thereof;
FIG. 3 is a rear view thereof;
FIG. 4 is a right-side view thereof;
FIG. 5 is a left-side view thereof;
FIG. 6 is a top view thereof; and,
FIG. 7 is a bottom view thereof.

The broken lines in the drawings depict portions of the electronic earmuff that form no part of the claimed design.

1 Claim, 7 Drawing Sheets
